UNITED STATES PATENT OFFICE.

JOHN JONES AND ALEXANDER GILLIES, OF TORONTO, CANADA, ASSIGNORS
TO JAMES EDWARD KNOX, OF SAME PLACE.

STREET-SWEEPER.

SPECIFICATION forming part of Letters Patent No. 599,937, dated March 1, 1898.

Application filed June 28, 1897. Serial No. 642,583. (No model.)

To all whom it may concern:

Be it known that we, JOHN JONES and ALEXANDER GILLIES, of the city of Toronto, in the county of York, in the Province of Ontario, Canada, have invented certain new and useful Improvements in Sweepers, of which the following is a specification.

Our invention relates to improvements in sweepers; and the object of the invention is
10 to design a simple and easily-adjusted form
of auxiliary brush by which the gutters and
sides of the streets may be effectually swept;
and its consists, essentially, of a brush con-
nected by a universal joint to the end of the
15 shaft of the main rotating brush, such auxil-
iary brush being suitably journaled on bar-
hangers connected to the bottom of the frame
of the wagon, and the parts being constructed
and arranged in detail as hereinafter more
20 particularly explained.

Figure 1 is a perspective view of a street-
sweeper provided with our improvement,
parts being broken away. Fig. 2 is an en-
25 larged perspective sectional detail of the outer
end of the auxiliary brush. Fig. 3 is a per-
spective detail of the outer journal-sleeve.

In the drawings like letters of reference in-
dicate corresponding parts in each figure.

A is the main body or floor of the wagon.
30 B are the front wheels, and C are the rear
wheels.

D is the auxiliary circular brush, which is
provided with a central axle E, connected by
a universal joint e to the end shaft F of the
35 main brush G.

D' is the hub of the auxiliary brush, which
is provided with cup-shaped ends D² and D³,
which are secured to the ends of the hub D'.
The hub is preferably made of wood to re-
40 ceive the bristles of the brush and has the
flanges d² and d³ secured to the ends. The
inner ends of the cup-shaped ends D² and D³
are secured to the axle E.

H is a bracket secured to the lower end of
45 the hanger-bar I, the upper end of which is
pivotally connected to the hanger-bracket J,
secured to the bottom of the sweeper. The
bracket H has a cylindrical rear end H',
through which extends the sleeve K, having
50 a flanged inner end k, which projects behind
the inner end of the cylindrical rear end H'

of the bracket. The inner end of the sleeve
K fits also within the cup-shaped end D² and
has the axle E' extending through it.

L is a bracket journaled on the axle F of 55
the main brush G and connected by the bar-
hanger L' to a suitable bracket l on the bot-
tom of the body.

M is a chain connecting the hanger-bars I 60
and L'.

N and O are rods having forked ends n
and o, respectively, which are pivotally con-
nected to lugs h and l' at the tops of the
brackets H and L, respectively.

P is a lever pivotally connected to the top 65
of the rod N, fulcrumed on the bracket P'
and extending through the metal strap P²,
secured to the top of the body.

Q is a lever pivotally connected at the top 70
of the rod O and fulcrumed on the bracket R.

Q' is a lever at the opposite side, also ful-
crumed on the bracket R.

S is a connecting-rod connected at one end
by the links s to the lever Q and at the other
end by link s' to the lever Q'. 75

T is the operating-lever, which is suitably
connected at one end to the connecting-rod S,
is fulcrumed at t on the bracket T' and ex-
tends at the forward end through the metal
strap U, secured to the top of the body. The 80
main-brush-operating lever T extends across
the end of the lever P, and thus when lever T
is operated the lever P is operated simulta-
neously therewith. A pin u extends through
the metal strap U above the lever, so as to 85
hold the connecting-rod and its coacting le-
vers and brushes at any desired height.

Having now described the principal parts
involved in our invention, we shall briefly
describe its utility. The brushes of course 90
are driven in the usual manner, preferably
from the opposite side of the machine to that
shown in the drawings, and the auxiliary brush
and main brush may be raised and lowered
through the connecting-rods by the lever T 95
hereinbefore described. The chain M, con-
necting the bar-hangers I and L' together,
serves to keep the journals of the auxiliary
brush D in position and thereby permit of the
rotation of the brush through the universal- 100
joint connection e between the ends of the
axle E and the ends of the axle F of the main

brush. The auxiliary brush formed in the manner such as we describe, it will be readily seen, serves to clean out the gutters next the curb, as such brush may be raised and lowered at the outer side into any desired angle through the series of holes at the top of the rod N.

In utilizing the auxiliary brush we wish it to be understood that the hind wheel is the 10 guide for the driver, as it passes along close to the curb, and the outside of the brush is situated just inside the wheel, so as to protect it and at the same time utilize the brush very close to the curb. It will also be understood that the distance between the front 15 wheels is very much less than that between the rear wheels.

The sleeve, which is journaled in the rear cylindrical end of the bracket H, is also made 20 to fit such cylindrical end loosely, so that the bearing will not bind when the brush rotates and is in a canted position. The sleeve K does not revolve itself, but is held from turning by a feather-key k' in the cylindrical end, 25 and being loose is permitted of being slightly canted in its bearing.

What we claim as our invention is—

1. In combination, the main brush, the auxiliary brush situated to one end of the main 30 brush and a suitable axle therefor, a universal-joint connection between such axle and the axle of the main brush, the hub, cup-shaped ends for the same secured to the axle, the inner and outer end brackets and bar-hangers connected thereto and pivotally supported at the bottom of the wagon and means for preventing the lateral displacement of the bar-hangers at their rear ends as and for 35 the purpose specified.

40 2. In combination, the main brush, the auxiliary brush situated to one end of the main brush and a suitable axle therefor, a universal-joint connection between such axle and the axle of the main brush, the hub, cup-

shaped ends for the same secured to the axle, 45 the inner and outer end brackets and bar-hangers connected thereto pivotally supported at the bottom of the wagon and a chain connecting the bar-hangers as and for the purpose specified.

50 3. In combination, the main brush, the auxiliary brush situated to one end of the main brush and a suitable axle therefor, a universal-joint connection between such axle and the axle of the main brush, the hub, cup-shaped ends for the same secured to the axle, 55 the inner and outer end brackets and bar-hangers connected thereto pivotally supported at the bottom of the wagon, the cylindrical rear end formed in the outer bracket, the sleeve through which the axle extends having an inner flange designed to project against the inner end of the cylindrical rear end of the bracket and means for preventing lateral displacement of the bar-hangers at their rear 60 ends as and for the purpose specified.

4. In a sweeper or like machine, in combination the main brush, lever mechanism for adjusting the same, the auxiliary brush situated to one end of the main brush and a 70 suitable axle therefor, a universal-joint connection between such axle and the axle of the main brush, suitable journals for the auxiliary brush supported from the frame of the machine, a vertically-adjustable rod connected at its lower end to the journal-box at the outer end of the auxiliary brush, the operating-lever suitably pivoted and connected to said rod and the main-brush-operating lever extending over the inner end of the auxiliary-brush-operating lever as and for the purpose specified.

JOHN JONES.
ALEXANDER GILLIES.
